UNITED STATES PATENT OFFICE.

AUGUST H. CAILLOUETTE, OF NASHVILLE, TENNESSEE.

OIL-BURNER.

1,269,258.

Specification of Letters Patent. Patented June 11, 1918.

Application filed September 7, 1917. Serial No. 190,185.

To all whom it may concern:

Be it known that I, AUGUST H. CAILLOUETTE, a citizen of the United States, residing at Nashville, in the county of Davidson and State of Tennessee, have invented certain new and useful Improvements in Oil-Burners; and I do hereby declare the following to be a full, clear, and exact description of the invention, such as will enable others skilled in the art to which it appertains to make and use the same.

This invention relates to burners for burning heavy hydrocarbon oil, such as kerosene, and more particularly to a burner wherein the oil is forced to the burner by air pressure.

More specifically, the object of this invention is to provide a burner of this nature which is extremely simple in construction, comprising an outer shell having both ends open, and a circular head or plug inserted in its lower open end through which the neck of the burner coil extends, and which neck has a flexible conduit connected thereto for feeding the oil to the burner coil.

A further object of the invention is to provide a burner coil which has a plurality of openings formed in one side of the same, and also a plurality of openings formed in the surface of the uppermost convolution of the burner coil.

With the foregoing and other objects in view, this invention consists in such novel features of construction, combination and arrangement of parts as will be hereinafter more particularly described, illustrated in the accompanying drawings, and claimed.

In describing the invention in detail, reference will be had to the accompanying drawings wherein like characters designate like and corresponding parts throughout the several views, and in which:

Figure 1 is a side elevation of the improved burner, showing the same connected to the supply tank,

Fig. 2 is a vertical section through the burner,

Fig. 3 is a horizontal section on the line 3—3 of Fig. 2,

Fig. 4 is a section on the line 4—4 of Fig. 2, and

Fig. 5 is a bottom plan of the burner.

Referring to the drawings, 1 designates the casing of the burner, which casing or shell is preferably cylindrical in shape and has both of its ends open. The lower end

of the cylindrical casing or shell 1 of the burner is reinforced, as shown at 2, and a plurality of set screws 3 extend through the reinforced portion 2, at spaced intervals, about the circumference of the cylinder and they extend into recesses 4 formed in the edge of a head or closure plate 5, which fits snugly within the lower end of the casing 1. The head 5 is provided with a plurality of openings 6, which extend therethrough and communicate with the interior of the casing above the head 5.

The head 5 is also provided with an opening 7, through which the neck 8 of the burner coil 9 extends. The burner coil 9 is formed of a coiled pipe, and is gradually tapered in diameter, as it extends upwardly, so that the uppermost convolution 10 of the coil is smaller in diameter than the lowermost convolution 11, as clearly shown in Fig. 2 of the drawings. The upper innermost convolution 10 is provided with a plurality of spaced openings 12, which communicate with the interior of the pipe coil 9 and permit of the egress of the fuel therefrom.

Certain of the convolutions of the coil 9 are provided with openings 13 formed in the sides thereof, which permit a limited quantity of the fuel to pass therefrom for the purpose of heating the coil 9 and facilitating the action of the same.

The neck 8 of the coil 9 has a coupling member 14 mounted thereon to which a flexible conduit 15 is connected. The flexible conduit or hose 15 is connected to a pipe 16, which extends downwardly within the retaining tank 17, to within a short distance of the inner surface of the bottom of the tank, as clearly shown in Fig. 1 of the drawings. A valve 18 is positioned in the pipe 16 for controlling the flow of fuel therethrough. A pipe 19 and a pipe 20 communicate with the top of the tank 17, and one of these pipes is provided for the inlet of oil into the tank, while the other is an air pipe, for conducting air into the tank. Valves 21 are carried by each of the pipes 19 and 20 for controlling the passage of fluid therethrough. A safety valve 22 is carried by the tank 17 so as to allow the escape of air, in case the same goes above a predetermined pressure within the tank. A gage 23 is also carried by the tank for determining the air pressure therein.

The flexible conduit 15 will permit the

burner structure to be placed at any desired angle.

In the operation of the improved burner; the fuel is forced from the tank 17 by the 5 air pressure therein, through the conduit 15 and upwardly into the burner coil 9, and after the fuel has started into the burner coil a piece of ignited waste, or any suitable material, is placed beneath the head 5, so 10 that the flame therefrom will pass upwardly through the openings 6, and this flame will ignite the fuel passing out of the openings 13 and also ignite the fuel passing out of the openings 12, and start the operation of 15 the burner.

From the foregoing description taken in connection with the accompanying drawings, the advantages of construction and of the method of operation of the improved oil 20 burner will be readily apparent to those skilled in the art to which this invention pertains, and while in the foregoing description, the principle of the operation of this invention has been described, together with 25 various features of construction, it is to be understood that certain minor features of construction, combination and arrangement of parts may be altered to suit practical conditions provided such alterations are com- 30 prehended within the scope of what is claimed.

What is claimed is:

1. In an oil burner, a cylindrical casing,

a head detachably carried by one end of said casing, a burner pipe oil positioned within 35 said casing and having its convolutions gradually decreasing in diameter as they extend upwardly, the uppermost convolution of said coil being provided with a plurality of spaced fuel egressing openings, said head 40 provided with a plurality of openings communicating with the interior of said casing, and fuel-conducting means connected to said coil.

2. In an oil burner, a cylindrical casing, 45 a head detachably carried by one end of said casing, a burner pipe coil positioned within said casing and having its convolutions gradually decreasing in diameter as they extend upwardly, the uppermost convolution of said coil being provided with a plurality of spaced fuel egressing openings, 50 said head provided with a plurality of openings communicating with the interior of said casing, and fuel conducting means connect- 55 ed to said coil, certain of the convolutions of said coils provided with openings formed in one side thereof through which fuel flows for heating the coil upon ignition of the fuel flowing therefrom.

In testimony whereof I affix my signature in presence of two witnesses.

AUGUST H. CAILLOUETTE.
